201,433

CHAIR

Warren Platner, 100 Mansfield Road,
North Haven, Conn.

Filed Feb. 20, 1963, Ser. No. 73,654

Term of patent 7 years

(Cl. D15—1)

FIGURE 1 is a front perspective view of a chair, showing my design;

FIGURE 2 is a front elevational view on a reduced scale;

FIGURE 3 is a side elevational view;

FIGURE 4 is a rear elevational view;

FIGURE 5 is a top plan view; and

FIGURE 6 is an enlarged fragmentary view of the forward edge of the leg pedestal taken along the line 6-6 of FIGURE 2.

The side of the chair not shown is like the side shown.
I claim:

The ornamental design for a chair, substantially as shown and described.
